UNITED STATES PATENT OFFICE.

FRANK McLAUGHLIN, OF OTTAWA, ONTARIO, CANADA.

POWDER DISPENSER.

1,416,043.

Specification of Letters Patent. Patented May 16, 1922.

Application filed December 26, 1919. Serial No. 347,382.

To all whom it may concern:

Be it known that I, FRANK McLAUGHLIN, a citizen of the United States of America, and resident of Ottawa, in the Province of 5 Ontario, Dominion of Canada, have invented certain new and useful Improvements in Powder Dispensers, of which the following is a specification.

This invention relates to dispensers, de-10 signed for use with powdered soap, toilet powders, medicinal powders, and powders generally, and the objects of the invention are to facilitate dispensing a quantity of powder adequate for the required purpose, 15 to render the dispenser water and moisture proof, airtight and germ proof under all conditions, and other objects which will be made clear hereafter.

In the accompanying drawings, an em-20 bodiment of my invention is illustrated with reference to a lather brush, but it should be understood that I do not limit myself to such an arrangement, which is only illustrative of one application of the invention.

25 In the drawings.

Figure 1 is an elevation of an embodiment of my invention.

Figure 2 is a longitudinal section of the device shown in Figure 1.

30 Figure 3 is a transverse section through the dispensing device shown in Figure 2.

Figure 4 is a fragmentary longitudinal section of a dispenser showing an alternative method of ejecting the powder.

35 Figure 5 is a fragmentary enlarged vertical section of a lateral wall of a dispenser showing the dispensing mechanism in outward position.

Figure 6 is a vertical section through the 40 cover or cap of the dispenser.

Like characters of reference refer to like parts in the several figures.

Referring to the drawings, A represents a 45 powder dispenser, which in the embodiment illustrated is utilized in conjunction with a lather brush B, but the dispenser may be used individually, and its use is largely governed by the nature of the powder being dispensed.

50 The dispenser A comprises a casing 10, having a lower closed conical end 11, which is engaged with the lather brush B, and the opposite end of the casing is closed by a cover or cap 12, which frictionally fits the 55 end of the casing and is provided with a

plurality of resilient arms 13, having projections 14 on the ends adapted to engage with recesses 15 in the periphery of the casing 10.

The cap 12 has its lateral wall offset out-60 wardly as shown at 19, and the transverse wall of the cap is concave, and the cap will permit of stability being given to the casing when it is upended.

Adjacent to the lower end of the casing 10, a conduit 17 extends from the lateral wall, this conduit having a flanged end 18, 65 which bears against the inner wall of the casing to give adequate support to the outer end of the conduit, on which the greatest forces are exerted.

In alignment with the conduit 17, is a cylinder 19^x having an outer flanged end 20, which engages the lateral wall of the casing, and gives a proper support to the inner end 70 of the cylinder, which is provided with a plurality of peripheral apertures or slots 21.

A rod 22 is slidably mounted in the cylinder 19^x, and conduit 17, and the end of the rod adjacent to the conduit is formed with a closing member 23, which frictionally en-80 gages the inner wall of the conduit, and the opposite end of the rod is formed with an enlarged finger or thumb press 24, which slidably engages the cylinder 19^x.

The member 23 is normally closed by a 85 spring 25, which encircles the rod 22, and is located between the inner end of the cylinder 19^x and the finger or thumb press 24.

The rod 22 carries an ejecting compressing and retaining member 26, which is spaced 90 from the closing member 23, and consists of a plate or disc having a peripheral flange 27 forming a dished head.

When the casing 10 is to be filled with soap powder, the user grips the casing 10 95 in one hand, and the cover or cap 12 in the other hand, and applies a pull longitudinally to the cover, whereupon the projections 14 of the resilient arms 13 are disengaged from the recesses 15, allowing the cover or cap 12 100 to be removed, leaving the upper end of the casing open for filling purposes.

On replacing the cover or cap 12, the projections 14 on the resilient arms 13 re-105 engage the recesses 15, so holding the cap in position.

Some of the powder in the lower end of the casing 10 will fill the conduit 17, and will also collect between the closing member 23 and the member 26, and on moving the rod 110

22 longitudinally under thumb pressure applied to the thumb press 24, the soap powder held between the closing member and ejector will be dispensed through the conduit, the 5 ejector cutting off any excess of powder from the casing, so that only a predetermined quantity of powder will be discharged through the conduit.

The conduit 17 acts as a stationary measuring device.

After dispensing this powder the thumb pressure is released from the thumb press 24, and the rod 22 is retracted by the spring 25, so that the closing member 23 closes the conduit 17.

This dispensing operation is repeated each time it is desired to dispense powder, and if soap powder is being dispensed it is discharged into a shaving cup, and lathered in 20 the ordinary manner.

Referring now to Figures 4 and 5, the casing 10 is provided with a conical valve seat 28, with which the closing valve 29 mounted on the rod 22 engages, and the outer face of 25 the valve 29 is rounded, to drain off any water which runs from the brush B down on to the casing, so that no water can enter the casing and mix with the soap.

The ejector 30 is the facsimile of that previously described, but it is so arranged that 30 it will embrace the inner end of the conical valve seat 28, as shown in Figure 5, during the dispensing of powder.

The cylinder 19, finger press 24, and spring 35 25 is the same as described above, and need not be enlarged on.

When using a dispenser of this type, the powder is retained between the valve 29, and the ejector 30, and when the rod 22 is moved 40 longitudinally under thumb pressure, then the powder between the valve seat 28 and the ejector 30 is compressed and discharged.

The ejector 30 embraces the inner end of the valve seat 28, and cuts off the supply of 45 soap from the casing, so that only a predetermined quantity of soap is discharged on the actuation of the rod 22.

The valve 29 is returned to its normal position by the spring 25, when the thumb pressure is removed from the member 24.

After each dispensing operation, the powder collects around the rod 22 between the ejector and the valve, and will be dispensed during the subsequent operation of the said 55 rod.

The object of forming apertures or slots 21 in the cylinder 19 is to allow any powder which may collect in the cylinder being returned into the casing 10 during the outward 60 movement of the rod 22, and thus the powder cannot impair the action of the spring 25 by clogging therearound.

The brush B is held by resilient means on the casing 10, and comprises a cap portion 35, one portion of which is formed conical 65 as shown at 36 to engage with the conical end 11 of the casing 10, and a plurality of resilient fingers 37 are provided, having projections 38 in the end which engage with depressions in the outer wall of the casing 10. 70

The cap portion 35 is formed with a conical end 39, which is separated from the conical portion 36 by the wall 40, which is provided with a peripheral flange rolled into position to engage the annular recess 41 provided at the junction of the conical portions 39 and 36 respectively.

The bristles of the brush B are set in rubber in the conical portion 39.

When removing this brush, the outer face 80 of the wall of the annular recess 41 provides a finger grip, which is gripped by one hand of the user, and the casing 10 is gripped by the other hand, and when a longitudinal pull is applied to the brush, it will be bodily removed from the casing.

It should be noticed that in replacing a brush the conical portion 11 of the casing 10 acts as a guide for the resilient fingers 37 and assists in spreading the same.

The conduit 17 and cylinder 19 are so arranged that water flowing down from the brush on the outside of the casing cannot enter and mix with the soap.

As many changes could be made in the 95 above construction, and many apparently widely different embodiments of my invention, within the scope of the claim, constructed without departing from the spirit or scope thereof, it is intended that all matter contained in the accompanying specification and drawings shall be interpreted as 100 illustrative and not in a limiting sense.

What I claim as my invention is:—

A dispenser for material in powdered 105 form comprising a powder containing casing having a laterally directed powder discharge orifice in its wall, an annular flange surrounding such orifice, a spring held plunger rod having a head having its exterior diameter corresponding in diameter to the interior diameter of the annular flange and provided with a narrow annular edge portion fitting within and around the interior periphery of the flange, manual means for operating the plunger rod to carry the head outward clear of the flange and means following up the head during its outward movement and entering the annular flange for ejecting the powder interposed between such head and 115 the ejecting means when the head is clear of the flange.

FRANK McLAUGHLIN.
